Primary Examiner — Mitchell I. Siegel

Assistant Examiner — Rochel L Rimelspach-Zare

(74) Attorney, Agent, or Firm — Cynthia S. Lamon;
Lamon Patent Services(57) CLAIM

I claim the ornamental design for golf club holder, as shown and described.

DESCRIPTION

FIG. 1 is a rear perspective view thereof.

FIG. 2 is top view thereof.

FIG. 3 is a bottom view thereof.

FIG. 4 is a left side elevation view thereof.

FIG. 5 is a right side elevation view thereof.

FIG. 6 is a front elevation view thereof.

FIG. 7 is a rear elevation view thereof; and,

FIG. 8 is a reduced front perspective view.

The broken lines in the drawings form no part of the claimed design.
